HEATING UNIT

Albert G. Goetz, Louisville, Ky.

Application September 9, 1943, Serial No. 501,637

1 Claim. (Cl. 20—1.11)

This invention relates to coal heating for houses, and aims to provide a regulated fuel supply and ash removal unit situated in the basement but isolated therefrom so that no coal or ash refuse can enter the basement, thus providing a clean and sanitary heating unit which is built into the house from the beginning.

Another object of the invention is the provision of a regulated or controlled fuel feed for the furnace, adapted to be operated automatically by the thermostat in the upstairs room, in the usual manner, and in conjunction therewith a blower for controlled forced draft.

The above and other objects will become apparent in the description below, wherein characters of reference refer to like-numbered parts in the accompanying drawings. It is to be noted that the drawings are intended to serve the purpose of illustration only, and it is neither intended nor desired that the invention be limited in any manner to the specific details of construction shown excepting insofar as the same may be essential to the invention.

Referring briefly to the drawings,

Fig. 1 is a plan view of the basement of a house provided with the unit.

Fig. 2 is a cross-sectional elevational view taken on the line 2—2 of Fig. 1.

Fig. 3 is a front elevational view of the unit.

Fig. 4 is a rear elevational view of the unit.

Fig. 5 is an enlarged side view, partly in section, of the regulated fuel feed.

Fig. 6 is a cross-sectional view taken on the line 6—6 of Fig. 5.

Fig. 7 is a cross-sectional view taken on the line 7—7 of Fig. 5.

Referring in detail to the drawings, the numeral 10 indicates the basement compartment of a house or building, having the floor 11 and ceiling 12, and the surrounding walls 13, 14, 15 and 16. The heating unit comprises, and is confined between, the side walls 17 and 18 thereof, the front wall 19, a partition wall 20, the top wall or roof 21, the wall 14 of the basement providing the closure of the unit compartment at that end. All the enclosing walls are preferably made of suitable and durable fireproof material, of which reinforced concrete would be a good example.

The upper portion of the unit comprises a coal hopper 22 having a floor 23 sloping downward away from the wall 14, and enclosed by the wall 19 at one end and the wall 24 at the other, as well as the said floor and the ceiling 21, and the

two side walls 17 and 18. A door or window 25, on hinges or the like, not shown, is provided in the wall 24, and directly adjacent thereto a similar door or window, or an opening, 26, is provided in the wall 14, and thereby fuel may be chuted into the hopper from outside the house.

The furnace 27 is mounted below the lowermost end of the floor 23, and a partition 28 extends from the floor 11 to the floor 23, between the walls 17 and 18, with the forward portion of the furnace projecting therethrough, thus sealing off the said forward portion of the furnace within the unit compartment 28. Thus the furnace doors 29 and 30 are accessible only from within the unit compartment 28. The chimney connection for the furnace is shown at 31, and also on the outside of the furnace, as the rear, is secured a forced draft blower 32 which blows into and under the fire grate of the furnace, not shown. Wires 33 extend from the electric motor of the blower.

A feed pipe or conduit 34 extends from an opening 35 through the hopper floor 23 at the lowest point thereof, down into the furnace above the fire grate, whereby coal is fed into the furnace. Below the opening 35, a cylinder 36 is rotatably mounted on pivots supported in the walls of the pipe 34, and a deformation or cut-out 37 is provided in the surface of the cylinder to provide a scoop or pocket whereby, during rotation of the cylinder, a measured amount of coal is fed down the pipe 34 during each rotation. An electric motor 38 is mounted outside the pipe 34, and by means of a belt 39 trained over the motor pulley 21 and the cylinder pulley 40, the cylinder is rotated by the motor 38. Wires 42 lead from the motor 38, and these, together with the blower wires 33, are adapted to be led, through the house current supply source, to a thermostat in a room of the house, not shown, in such manner that the fuel feed and the forced draft will be operated in conjunction when the room temperature descends to a pre-set level. A door 43 is provided through one unit wall, 18, for entrance into and exit from the unit compartment 28.

It is apparent from the above that ashes are removed from the furnace within the compartment 28, thus avoiding any messsing of the basement, and likewise no coal or coal dust can enter the basement, and the coal is stored right within the unit instead of having to be carried a distance thereto. Obviously, modifications in form and structure may be made without de-

parting from the spirit or scope of the invention. Ventilation of the unit compartment may be provided as desired.

I claim:

A structure for a house adapted to be mounted against one wall of the basement thereof with said wall providing one end wall for said structure, a pair of spaced side walls extending from said first wall, said side walls rising from the floor to the ceiling of the basement, a front wall extending partway down from said ceiling thereby leaving a space thereunder adapted to be occupied by a furnace, a sloping wall extending

from the bottom of said last-named wall upward toward the upper portion of said first-named wall and enclosing a hopper-like chamber thereabove, said sloping wall having an opening through the lowermost end thereof, and a partition positioned rearward of and parallel with and extending from said sloping wall down to the basement floor between said side walls and having an opening extending from said floor upward to a level intermediate the height of said partition, said furnace being adapted to project through said partition opening.

ALBERT G. GOETZ.
